UNITED STATES PATENT OFFICE.

DUTEE WILCOX FLINT, OF CRANSTON, RHODE ISLAND.

LIQUID-DISPENSING APPARATUS.

1,168,717.

Specification of Letters Patent. Patented Jan. 18, 1916.

Application filed February 13, 1915. Serial No. 8,054.

To all whom it may concern:

Be it known that I, DUTEE WILCOX FLINT, a citizen of the United States, and resident of the city of Cranston, in the county of Providence and State of Rhode Island, have invented certain new and useful Improvements in Liquid-Dispensing Apparatus, of which the following is a specification.

This invention relates to a liquid dispensing apparatus of the class more particularly adapted for supplying motor vehicles at the street curbing, and the invention has for its object to provide a main tank and an auxiliary tank located inside of a building or other convenient place clear of the side walk and to conduct the gasoline by gravity through a supply pipe extending from this auxiliary tank to the edge of the street curbing, said pipe being located underneath the side walk so as not to interfere with traffic thereover.

A further object of the invention is to provide means whereby that portion of the pipe directly located beneath the side walk is automatically emptied after each supplying operation.

It is found in practice that the laws of some cities prohibit the placing of a gasoline tank or other obstruction at the edge of the street curbing, or the carrying of cans of the liquid across the walk, it is also found that the running of a supply pipe either over or under the side walk is objectionable unless the pipe be drained of the liquid whenever it is not in use, therefore, in order to obviate these objections and conform strictly to the city ordinances, I have located the supply tank in a building to one side of the walk and have placed the pipe beneath the walk so that the liquid may be quickly supplied to vehicles at the curb without interfering with the side walk traffic and I have so positioned and connected the pipe that it will be immediately and automatically emptied of its contents after each filling operation.

With these and other objects in view, the invention consists of certain novel features of construction, as will be more fully described, and particularly pointed out in the appended claims.

In the accompanying drawings: Figure 1— is a diagrammatic view illustrating the general arrangement of my improved apparatus showing the supply pipe as extending to the curb beneath the side walk. Fig. 2—

is a sectional side elevation of the valve which is caused to shut off the supply from the gasoline tank and open the pipe to the main tank by the releasing of the flexible supply hose after each supplying operation. Fig. 3— is a section of the valve on line 3—3 of Fig. 2. Fig. 4— is a sectional side elevation showing the sliding closure at the curb for covering the aperture through which the hose is drawn when the same is not in use. Fig. 5— is a plan view showing the edge of the curb and the casing in which the closure slides.

In carrying out my invention, I have provided a main tank 10 located in a cellar or excavation beneath the building in which the apparatus is stored and I have provided an auxiliary tank 11 located above the main tank and enough higher than the vehicles in the street to run the gasoline therefrom into the vehicle tank by gravity. In supplying the auxiliary tank from the main tank I preferably provide a pump 12 driven by motor 13 which draws the gasoline up through the pipe 15 into this auxiliary tank. I have also provided a supply pipe 16 which extends downward from the auxiliary tank and is connected at the point 17 with the valve 18 at the point 20 with the return pipe 19 leading back to the main tank 10. The member 21 of this valve is shown as being in a plug form having a hollow stem portion 22 to which the flexible supply hose pipe 23 is connected. This pipe, when not in use, hangs down in a loop form to take up its slack, and passes up through the conduit 24, and its end which is supplied with the valve nozzle 25 is adapted to lie inside of the pocket 26 beneath the surface of the side walk completely out of the way.

In order to form a suitable pocket or enclosure for the opening through the side walk, necessary to permit the hose to be drawn out therethrough, I have provided a metal casing 27, which is preferably rectangular in shape having an opening at 28 sufficient to permit a plate 29 adapted to slide in grooves 30 to be moved back and permit the passage of the nozzle and hose when desired to be drawn out for use and to slide forward and effectually close the opening when the hose is dropped back into the pocket. Friction rolls 36 are provided about the edge of the opening to prevent undue wear upon the hose while moving in and out. A lock 31 is mounted in the casing having a

bolt 35 which is adapted to be moved to secure the plate when closed requiring a special key for releasing the same. This casing is set into the side walk flush with its face at the curbing, and the closure is provided with a counter-weight 37 connected by cord 38 to automatically close the same as soon as the hose has been pushed back out of the way, thus preventing all possibility of accident to passing pedestrians.

To assist in withdrawing the hose from the side walk back into the cellar after each operation, I have connected an arm 32 to the rotatable portion of the valve to move with the hose and have connected the outer end of this arm to the hose by the strap 33, and on this arm I have mounted a counter-weight 34 adapted to be adjusted along the bar and attached where its weight will insure a quick withdrawal of the flexible pipe into the cellar, as soon as released by the operator after the supplying of each vehicle. This return movement of the hose is facilitated by the placing of the conduit 24 on an incline, whereby the hose by its own weight would have a tendency to fall back into the cellar.

To the auxiliary tank 11, I have connected a glass tube 37 which is positioned in plain view of the customer and by which the exact level of the liquid in the tank may be observed. On this tube, I have mounted a sliding gage 38 which may be adjusted along the tube and set in position so that it will assist in indicating to the customer the amount he is receiving.

The operation of my improved invention may be more clearly described as follows— The auxiliary tank is supplied from the main tank and is set at a height to supply the vehicles in the street by gravity through the pipe 16 and hose 23. When a vehicle drives up to the curb the attendant slides back the cover 30 from the casing which is set flush with the curbing and the side walk, reaches into a chamber 26 and draws out the supply nozzle end of the hose and positions the same into the tank of the waiting vehicle. The act of drawing the hose straightens its loop portion in the cellar and through this movement operates the valve 18 to automatically close the return pipe 19 to the main tank and simultaneously open the passage-way from the supply pipe 16. The gasolene now runs from the auxiliary tank into the hose 23 and as soon as this hose is filled the attendant sets the sliding scale so that the zero mark on the gage will correspond with the height of the liquid showing in the tube. The amount drawn is then denoted on the gage by the falling of the liquid in the tank, and when sufficient has been drawn for the customer, the valve at the nozzle is closed and the semi-flexible hose is drawn into po-

sition illustrated in Fig. 1. This action automatically closes the supply from the auxiliary and opens the return to the main tank. The attendant now simply opens the valve at the supply nozzle and drops the same into its pocket the cover to which immediately closes and the liquid from the hose drains back into the main tank. This operation is repeated as each customer presents his motor vehicle at the curbing.

I claim:

1. In an apparatus for dispensing volatile liquids, the combination with a side-walk having an opening therein near its curb, of a supply tank located to one side of said walk and a readily extendible delivery pipe leading from said tank on an incline to said opening and located below the surface of said walk, said curb opening forming a receptacle for the hose nozzle.

2. In an apparatus for dispensing volatile liquids, the combination with a sidewalk having an opening therein, of a supply tank located to one side of said walk and a flexible pipe leading from said tank to said opening and arranged to be moved through said opening and means for permitting said pipe to drain when in its inner position.

3. An apparatus for dispensing volatile liquids comprising a sidewalk provided with an opening near its curb, a supply tank set to one side and below the surface of said walk, a pipe leading from said tank beneath said walk to said opening and means for permitting that portion of the pipe beneath the walk to drain after each filling operation.

4. An apparatus for dispensing volatile liquids comprising, a sidewalk provided with an opening near its curb, a supply tank set to one side and below the surface of said walk, a pipe leading from said tank beneath said walk through said opening and capable of being readily-extended through and withdrawn from said opening.

5. An apparatus of the character described, comprising a sidewalk, a supply tank set to one side and below the surface of said walk, a chamber in the walk adjacent the curbing, an inclined conduit leading from said chamber beneath the walk, a readily extendible pipe leading from said tank through said conduit into said chamber, and means for covering the opening to the chamber, when the end of the pipe is housed therein.

6. An apparatus for dispensing volatile liquids comprising a side-walk having an opening therethrough, a supply tank, a pipe leading from said tank beneath said sidewalk through said opening, means whereby said pipe may be readily extended through and withdrawn from said opening, a closure for said opening, and means for automatically moving said closure to close the open-

ing when the end of the pipe has been deposited therein.

7. An apparatus for dispensing volatile liquids comprising a side-walk provided with an opening, a supply tank, a pipe leading from said tank beneath the side-walk to said opening, said pipe being arranged to be readily extended through and withdrawn from said opening and means for draining that portion of the pipe remaining beneath the walk when the same is withdrawn.

8. An apparatus for dispensing volatile liquids comprising a side-walk provided with an opening, adjacent the curb, a supply tank, a pipe leading therefrom beneath the side-walk to said opening, means whereby the withdrawing action of this pipe automatically causes the liquid to drain from said pipe.

20 9. An apparatus for dispensing volatile liquids comprising a sidewalk provided with an opening, a supply tank, a pipe leading therefrom beneath the side-walk to said

opening, means whereby a portion of said pipe may be readily extended and withdrawn through said opening, a control valve in the pipe line and means whereby the act of extending said pipe opens the supply and closes the discharge and the withdrawal of said pipe closes the supply and opens the discharge to permit the pipe to drain.

10. An apparatus of the character described, comprising a sidewalk provided with an opening, a supply tank set to the side of said side-walk opposite to that of the curbing, a chamber in the walk adjacent the curbing, a pipe extending from the tank beneath the walk, and means for covering the opening to the chamber when the end of the pipe is housed therein.

In testimony whereof I affix my signature in presence of two witnesses.
